UNITED STATES PATENT OFFICE.

SARAH LORD MURPHY, OF NEW YORK, N. Y., ASSIGNOR TO MAYFAIR, INC., OF NEW YORK, N. Y., A CORPORATION OF NEW YORK.

DESIGN FOR A CHAIR-RACK.

45,237.

Specification for Design.

Patented Feb. 10, 1914.

Application filed December 6, 1913. Serial No. 805,165. Term of patent 3½ years.

To all whom it may concern:

Be it known that I, SARAH LORD MURPHY, a citizen of the United States, residing at New York, in the county of New York and State of New York, have invented a new, original, and ornamental Design for Chair-Racks, of which the following is a specification, reference being had to the accompanying drawing, forming part thereof.

Figure 1 is a view in front elevation of a

chair rack, showing my new design, Fig. 2 is a view in end elevation of the same, Fig. 3 is a view in rear elevation of the same.

I claim:

The ornamental design for a chair rack, as shown.

SARAH LORD MURPHY.
